UNITED STATES PATENT OFFICE.

HELMER N. JAHRN, OF GULL LAKE, SASKATCHEWAN, CANADA.

SPEED-GOVERNOR.

1,264,806.

Specification of Letters Patent. Patented Apr. 30, 1918.

Application filed March 31, 1916. Serial No. 88,165.

To all whom it may concern:

Be it known that I, HELMER N. JAHRN, a subject of the King of Great Britain, residing at Gull Lake, in the Province of 5 Saskatchewan and Dominion of Canada, have invented certain new and useful Improvements in Speed-Governors, of which the following is a specification.

This invention relates to speed governors 10 for internal combustion engines, and has for its primary object the provision of a charge regulating means whereby the flow of combustible gas from the carburetor may be minutely regulated, thus, permitting but a 15 predetermined amount of fuel to pass to the engine.

The invention contemplates the provision of a device of the character described consisting of a shaft for carrying the usual 20 detent arm, supported in suitable bearings by the engine frame; the supporting shaft having arranged thereon a plurality of eccentric bearing surfaces; arms fixedly mounted on the said eccentric bearing surfaces, one of said arms having pivotally connected thereto, at its upper or outer extremity, the usual carburetor valve operating rod; a link member for connecting the 25 said arms and holding the same in an adjusted position, a lever being pivotally secured to one of said arms, while its remaining portion is provided with an elongated slot adapted to receive the sleeved portion arranged upon the remaining arm.

30 The annexed drawings and the following description set forth in detail such mechanism embodying the invention, such disclosed means constituting, however, but one of the various mechanical forms in which 35 the principle of the invention may be used.

In said annexed drawings;—

Figure 1 is a fragmental side elevation of an engine with my improved regulating device applied thereto;

40 Fig. 2 is a detail in top plan, partly in section, showing the arrangement of the regulating device upon the detached arm;

Fig. 3 is a section taken on the line 3—3 of Fig. 2;

45 Fig. 4 is a side elevation in detail of the device;

Fig. 5 is a detail in perspective of the eccentrically arranged supporting shaft; and

50 Fig. 6 is a detail in perspective of the connecting link.

Referring now more particularly to the drawings, wherein like reference characters denote like or corresponding parts throughout the several views thereof, reference will 60 be had to the construction of the engine which may be of any type, but which in the present embodiment is shown to be a horizontal engine. A supporting frame A is provided for carrying the cylinder B and 65 other various mechanism, which includes a drive shaft C having keyed thereto a spur pinion D, and also carries the usual centrifugal governing means, not shown, which means is connected with the sleeve E alined 70 with the drive shaft C. The gear or spur pinion D is connected with a spur gear F, which is of greater diameter, and carries the usual hand valve operating mechanism G. Rotatably supported by the frame A in 75 suitable bearings, is a supporting shaft 1, which shaft carries a conventional form of detent arm H. The said detent arm having arranged upon its outer extremity, adjacent the sleeve E, a roller I. The construction, 80 as shown, is that of the conventional horizontal engine, which is supplied with the usual hit and miss type governors and it is to be understood that the same forms no part of the present improvement, but is merely 85 illustrative.

Referring now to the present improvement, the supporting shaft 1 is provided with an annular recess 2, whereby the same may be secured in a manner to present lateral movement thereof in the frame A by means of a set screw 3, a portion of the shank engaging with said annular recess, consequently effectively serving to prevent endwise movement of the supporting shaft. 90

Arranged upon the outer extremity of the supporting shaft 1 is an eccentrically mounted sleeve 4, which sleeve, has secured at its outer end an arm 5, the arm being provided with, adjacent its upper extremity, an enlarged portion 6, said portion having arranged therein an aperture as at 7. This sleeve 4 may be constructed from brass, or of some other comparatively soft metal, thus, offering an efficient bearing surface for the second sleeve, which shall be subsequently described. The second sleeve includes an eccentrically mounted portion, as at 8, which surrounds the eccentric sleeve 4, thus offering, what might be termed, a double eccentric arrangement, while the outer end thereof has rigidly affixed thereto, an 105 110

arm 9, which arm is provided with, at its upper extremity, an enlarged portion 10, having a laterally extending sleeve 11, and has arranged therein, an aperture 11'. A 5 connecting link 12 having arranged adjacent one end thereof, an opening or aperture 13, and at its remaining end an elongated slot 14, is adapted to connect the arms 5 and 9, the arm 6 having arranged in the aperture 10 7, a bolt 15, which has threaded on its shank, a thumb nut 16, the shank extending through the elongated slot 14 of the connecting link 12, thus, serving as efficient means for affording the connection between these 15 two elements, while the arm 9 has passed through its aperture a right angularly disposed portion of the carbureter valve operating rod 17, as at 18, the said portion 18 also extending through the apertures arranged 20 in the remaining end of the connecting link 12, the said link being held thereby against lateral movement by means of a cotter pin 19, which is passed through the outer end of the portion 18 this serving as 25 sufficient securing means. It is to be understood that the rod 17 is connected with the control or supply valve of a carbureter, not shown, whereby the flow of fuel therefrom may be sufficiently regulated.

30 In operation and assuming that the operator desires to increase the flow of fuel from the carbureter, the arm 5 is moved backwardly in the elongated slot 14 to a position as shown in dotted lines, by Fig. 4, 35 whereupon the forward arm 9, will by means of the eccentric mounting, be moved forwardly and slightly upwardly to a position as shown to advantage in dotted lines in the said Fig. 4. When this desired adjustment 40 has been obtained, the thumb nut 16 is turned into engagement with the connecting link 12, thus serving as efficient means for securely binding or holding the elements in the adjusted position. It is obvious that 45 as the drive shaft C rotates, the speed governing mechanism, as carried thereby, will be so actuated as to pull the sleeve E outward, thereby causing the beveled portion to press upon the roller I, consequently, 50 forcing the same upwardly and causing the detent arm H to move downward, whereupon the exhaust valve, not shown, will be held open until the speed is reduced to normal. The sleeve E, moving back, allows the 55 detent lever to disengage the valve operating hand mechanism G, and the former cycle of operation is again taken up. During this operation, it will be noted that the arm 5 will actuate the supply valve operating rod 60 17, so as to close the same, thus facilitating the reduction of the speed.

It is obvious that as the sleeve E moves outwardly it will engage the roller I so as to cause the detent arm H to be swung for 65 retaining the exhaust in an open condition,

as hereinbefore specified. The sleeve on the detent H will obviously oscillate the sleeve 8. It should be specifically understood that the sleeve 8 is ordinarily held against independent movement with respect to the sleeve 70 of the detent by frictional engagement between these elements, such engagement may obviously be of considerable strength. The sleeve 4 which is positioned within the sleeve 8, is also held against independent 75 movement under ordinary conditions by frictional engagement. This frictional engagement between the sleeves is caused by a very snug fit, and for this reason, when the sleeve of the detent H is oscillated, in either 80 direction the oscillating motion will be imparted to the sleeves 8 and 4, thus causing the arms 5 and 9 to be rocked for reciprocating the rod 17. As before explained, the rod 17 is used for regulating the fuel supply 85 to the carbureter of the engine. When however, it is desired to shift the rod 17 to cause the maximum or else a minimum supply to the carbureter, prior to the starting of the engine, the thumb nut 16 may be unscrewed 90 so as to release the bolt 16 from engagement with the arm 5 and within the slot 14 of the link 12 and then the arms 9 and 5 may be gripped by the operator and swung away 95 from each other, thus moving the arm 5 toward the end of the slot in the link 12, when it is desired to have an increased supply of fuel to the carbureter. When it is desired to diminish the supply the arms 5 and 9 will be gripped and urged toward each 100 other and thus after the arm 5 has been moved to an adjusted position with respect to the slot 12, the nut 16 is again tightened upon the bolt 15 to cause the arms 5 and 9 to be retained in a set position with respect 105 to each other. It is obvious therefore, that when the detent arm H is rocked for opening the exhaust valve and allowing the engine to be cooled as rapidly as possible, after the speed has reached a predetermined 110 point, the shifting of the detent will cause the frictional engagement between the several sleeves to rock the arms 5 and 9 and thus shift the rod 17 to cut off further supply of fuel to the carbureter until the speed 115 of the engine has been reached to normal, and then as the sleeve E has been turned to its normal position to permit the roller L to resume its normal position, the detent 8 will return to its normal position and allow 120 the exhaust valve to again operate under normal conditions.

By providing the double concentric, hereinbefore specified, the shifting of the arm 5 to the outer end of the slot as illustrated in 125 dotted lines in Fig. 4 will cause the arm 9 to be shifted upwardly and forwardly as also indicated in dotted lines in this figure. This will cause the arm 9 to be shifted to such a position as when the engine is started, 130

the rod 17 will have been shifted to permit the maximum supply of fuel to the carbureter. Accordingly the speed of the engine will be increased by the adjustment above 5 specified. However, owing to the position of the arm 9, under such conditions, the shifting of the arms through the sleeve of the detent H will very quickly cut down the supply of fuel when the engine has exceeded 10 a predetermined speed. The shifting of the arm 9 by the double eccentric arrangement will cause the arm to have its outer end moved for considerable distance beyond the central axis of the shaft 1, which position of 15 the arm 9 will cause the same to have a greater relative movement than would be the case if a concentric mounting would not move the outer end of the arm 9 outwardly from the central axis of the shaft 1 and for 20 this reason the outer end of the arm 9 would at all times be swung in the arc of a circle, the diameter of which would be equal under all conditions. By having this device mounted upon the double eccentric mounting, as 25 specified, when the speed of the engine is to be materially increased, the outer end of the arm is shifted outwardly so that when it is swung it will move in the arc of a circle, the diameter of which would be greater 30 than the original diameter of the arc of the circle in which the arm originally moves in. Accordingly, although the rod 17 will be shifted to cause the maximum supply of fuel to the carbureter, the position at that time 35 assumed by the rod 17 and the arm 9 will be such that a very slight movement of the arm by the oscillation of its sleeve on movement of the detent arm will cause the supply to the engine to be quickly reduced for 40 reducing the speed of the engine.

I claim—

1. Speed governing mechanism, including, in combination with supply valve operating means, an eccentrically mounted arm associated with said means, means for connecting said arm with the supply valve whereby a predetermined flow of fuel through the supply valve will be permitted, and means connected with said arm for securing the 50 same in an adjusted position.

2. Speed governing mechanism, including, in combination with supply valve operating mechanism, of a plurality of eccentrically mounted arms associated with said mecha-

nism, a valve operating rod connected with 55 one of said arms, said arms being relatively adjustable for permitting a pre-determined flow of fuel through the supply valve, and means connected with said arms for securing the same in adjusted position. 60

3. Speed governing mechanism, including, in combination with supply valve operating mechanism, a supporting shaft, an eccentrically mounted arm carried by said supporting shaft, a second eccentrically mounted 65 arm arranged adjacent said first mentioned arm, a valve operating rod connected with one of said arms, said arms being relatively adjustable for controlling a predetermined flow of fuel through the supply valve, and 70 means connecting said arms for holding the same in adjusted position.

4. Speed governing mechanism, including in combination with supply valve operating mechanism, a supporting shaft, a sleeved 75 arm eccentrically mounted upon said supporting shaft, a second sleeved arm supported by said supporting shaft and arranged about the sleeve of the first mentioned arm, said sleeved arms being relatively adjustable for permitting a predetermined 80 flow of fuel through the supply valve, and means for securing the arms in adjusted position.

5. Speed governing mechanism, including, 85 in combination with supply valve operating mechanism, of a supporting shaft, a sleeved arm supported by said supporting shaft, a second sleeved arm supported by said supporting shaft and arranged about the sleeve 90 of said first mentioned arm, a supply valve operating rod pivotally connected with one of said arms, said arms being relatively adjustable for controlling a predetermined flow of fuel through the supply valve, a link 95 connecting the outer extremities of said arms, said link having arranged in one extremity thereof, an elongated slot adapted to receive a portion of the remaining arm and means for securing said arms in an adjusted 100 position.

In testimony whereof I affix my signature in presence of two witnesses.
